UNITED STATES PATENT OFFICE.

CHRISTOPHER C. WEAVER, OF CLEVELAND, OHIO

WATER-HEATER.

1,285,855.

Specification of Letters Patent. Patented Nov. 26, 1918.

Application filed February 23, 1917. Serial No. 150,605.

To all whom it may concern:

Be it known that I, CHRISTOPHER C. WEAVER, a citizen of the United States, residing at Cleveland, in the county of Cuyahoga and State of Ohio, have invented certain new and useful Improvements in Water-Heaters, of which the following is a specification.

The present invention relates to automatic water heaters for domestic use principally and of the type commonly designated as instantaneous. One of the objects of the invention is the provision of an apparatus for the purpose set forth, that is simple and economical in construction, providing the maximum of efficiency and minimum of cost for installation and upkeep. In the common practice for supplying hot water for domestic use, a tank or reservoir is employed and a pipe from the main water supply passes through the fire box of a furnace to said reservoir. Auxiliary gas heaters are also generally used for heating the water in the reservoir independent of the furnace, so that hot water may be provided when the furnace is for any reason out of commission. The reservoirs and auxiliary heaters are troublesome, inconvenient, and more or less expensive to install and keep in repair; therefore a further object of the present invention is the provision of a water heater that meets all the requirements without the employment of a reservoir in connection therewith. A further object is the provision of apparatus for the purpose set forth, that is automatically operative, the fuel supply for the purpose of heating the water being controlled by the pressure of the water, the construction and arrangement of parts being such that when water outlets are closed the heating medium is cut out, but immediately put into action upon the opening of a water outlet, thereby resulting in economy of fuel. Still a further object of the invention is the provision of precautionary means whereby the fuel supply is automatically cut off when the main water supply is closed, thereby eliminating the possibility of damage to the apparatus by burning dry tubes if the actuating means, or opening of outlets is inadvertently resorted to. With the above mentioned and other apparent objects in view, the invention consists in the construction, arrangement, and co-operative combination of the elements as shown in the

drawings, described in the following specification and pointed out definitely in the annexed claims.

In the accompanying drawings which 60 form a part of the specification, Figure 1 is a view in elevation of an embodiment of the improved heater and connections, showing one door removed and a small portion of the casing broken away. 65

Fig. 2 is a view of the assembled parts that are inclosed within the casing, the casing being removed, and the upper and lower headers being in central cross-section.

Fig. 3 is a plan view of the upper header. 70

Fig. 4 is a top plan view of the lower header, showing the burners and their connecting members.

Fig. 5 is a plan view of one of the coils used, showing its connection with mani- 75 folds.

Fig. 6 is a plan view of one form of a double control valve employed, and Fig. 7 is a section on line 7—7 of Fig. 6.

Fig. 8 is a plan view of a modified form 80 of valve, and Fig. 9 is a section on line 9—9 of Fig. 8.

To facilitate the understanding of the apparatus similar characters of reference are employed to designate similar parts 85 throughout the drawings and description.

As before stated the apparatus is intended principally for domestic use and for quickly heating water for any and all purposes desired. It occupies but a small volume of 90 space and may be located in any convenient apartment, preferably in the basement which is the usual location for apparatus of this character, and is connected with the water and gas pipes by the members W and 95 G respectively.

In the embodiment of the invention as illustrated, the body of the apparatus, or heater proper is supported by an ordinary standard 1 which is common and therefore 100 not an element of the invention. Two headers are provided, and for convenience of explanation they will be designated as upper header 2 and lower header 3. The headers 2 and 3 are spaced the desired distance apart 105 and are connected by manifold members 4 and 5. The upper header 2 consists of a hollow casting substantially as shown in Figs. 2 and 3, providing a continuous water chamber 6 in the hub 2^a, rim 2^b, and connecting arms 2^c. The lower header 3 is provided with a gas chamber 8. By referring

to Fig. 2 it will be seen that the manifold 5 has an open connection with the chamber 6, passes through the header 3, is connected with the pipe member 30 and closed by the cap 30^a, while the manifold 4 passes through the header 3 but has a closed or dead connection with the header 2. A series of tubular coils 9 are interposed between, and connected with the manifolds 4 and 5 and surround a flue member 10 which depends from a central opening 2^a in the header 2.

A water inlet pipe line 11, 11^a connects the water supply W with the chamber 6 at 6^a, and is provided with branches 12, 12^a and 13, 13^a, a water feed regulating cock 14 being interposed between said branch connections. The branches 12^a and 13^a lead to the control members 15 and 16 respectively. By referring to Figs. 6 and 7, the construction and operation of the control members will be understood. It will be seen that the members 15 and 16 are of similar construction and for convenience are embodied in the same housing. Each member comprises a water pressure controlled valve, but the function of valve member 15 is the reverse of that in member 16, as will now be explained. In member 15 the valve 15^a attached to the stem 15^b is held open by the water pressure on the head 15^c through the branch 12^a, and when pressure is relieved from the head 15^c the valve is closed by the spring 15^d. In member 16 the valve 16^a attached to stem 16^b is held closed by the water pressure on the head 16^c through the branch 13^a and when pressure is relieved from the head 16^c the valve is opened by the spring 16^d. The valve chambers 15^e and 16^e are connected by a port 16^e.

A pipe 17 connects the valve chamber 15^e with the gas supply G, and a pipe 18 connects the valve chamber 16^e with the fuel chamber 8 in the lower header 3, suitable burners 19 also being connected with the chamber 8 below the coils 9.

The outlet or service line 20 is connected with the manifold 4 as shown at 3^a. By following the connections as above described it will be seen that water from the inlet 11 passes through the chamber 6 into manifold 5, through the coils 9, manifold 4 to the service line 20. Water being turned on at the main, there is a constant pressure on the head 15^c through W, 11^a, and the branch 12, 12^a, this holds the valve 15^a open, allowing the gas to enter chamber 15^e, and through port 16^e to chamber 16^e. The water pressure on head 16^c closes the valve 16^a and cuts off the gas from the burners 19. A branch 21 connects the fuel pipe 17 with a pilot burner 22. Ordinary gas shut off cocks 23 and 24 are provided in the gas connections 17 and 21 respectively, and when the apparatus is in operative condition these cocks are open, thereby providing a constant supply of fuel to the valve chamber 15^e and the pilot 22.

The branch 13 is preferably of smaller bore than the inlet pipe 11, and when the service line 20 is opened at any point, as for example through the faucet 25, the pressure is relieved on the head 16^c and the valve 16^a is opened by the spring 16^d, thereby admitting the fuel to the burners 19 where it is ignited by the pilot flame, resulting in rapid heating of the water passing through the coils 9, the connecting manifolds, and the service line 20.

The manifolds, coils, burners, and upper header are inclosed within a casing 26, provided with doors 26^a thereby increasing the heat value by confinement.

The arrangement and co-operation of the parts is such that the opening of the outlet 25 results in almost instantaneous flow of hot water therefrom, and immediately upon the closing of the outlet the pressure through 13, 13^a closes the valve 16^a, thereby cutting off the fuel supply to the burners 19, but not interfering with the pilot.

The control member 15 provides a precautionary or safety element. In case the water supply is cut off at the main, or in the line W, the pressure on the head 15^c is relieved and the valve 15^a closes, thereby rendering the burners 19 inoperative. It will readily be seen that the principal object of the invention may be accomplished, and the operation of automatically controlling the fuel supply to the burners is the same if the safety element 15 is eliminated and the connection 17 made directly with the chamber 16^e.

It will be noted that the improved apparatus provides for a great saving of fuel, as the major fuel consumers, or burners 19 are only active when hot water is desired and an outlet or outlets in service line are opened.

An important feature of the invention is the simplicity of construction that facilitates repairs. If one of the coils 9 becomes damaged it can be quickly and easily removed, the manifold connection for the damaged coil plugged, and the apparatus is therefore only out of commission for a comparatively short time. The apparatus can be installed and kept in reliable operative condition by any person of ordinary intellect, and does not require the services of an expert in the heating and plumbing line.

While a preferred construction of control members is shown in Figs. 1, 6, and 7, these members may be made in a variety of designs and operate under the same principle and provide the same result, and therefore be within the scope of the invention. Figs. 8 and 9 are illustrations of a modified form of double control member wherein the water pressure from 12^a acting on the diaphragm 50^e holds the gas valve 50^a open against the force of the spring 50^d, and the pressure

- from 13^a on the diaphragm 60^c holds the valve 60^a on its seat, thereby shutting off the gas from pipe member 18. This construction is the equivalent of that shown in Figs. 5 1, 6, and 7, the functions of the parts being the same, the chambers 50^c and 60^c connected by the port 60^f being the equivalent of the chambers 15^c, 16^c and connecting port 16^f respectively.
- 10 The apparatus can be efficiently operated as a hot water circulating or return system by connecting the return pipe with the member 30, shown in Figs. 1 and 2 as closed by the cap 30^a.
- 15 While a practical embodiment of the invention is herein shown and described, it will be understood that I am not confined to this specific construction, as there may be various modifications of details in construction and arrangement of parts without departing from the nature of the invention, the limitations being governed by the scope of the claims and the existing state of the art.
- 20 25 What I claim and desire to secure by Letters Patent is.
1. In a water heater, the combination of a header member provided with a water chamber; a header member provided with a fuel chamber; manifold members forming spacers and supports for said headers, one only of said manifold members opening into the water chamber; a series of tubular coils arranged between the headers and connected with said manifolds; fuel burners connected with the fuel chamber below the coils; a water inlet member connected with the water chamber; a fuel supply member connected with the fuel chamber; and a control valve in the fuel supply line.
  2. In a water heater, a header provided with a water chamber; a water supply connected with said chamber; a manifold member having open connection with said chamber; a manifold having a closed connection with said header; a series of separate heating coils interposed between and connected with said manifolds; a header provided with a fuel chamber, located below the coils, said header being supported by the manifolds; a fuel supply member connected with said fuel chamber; burners connected with said fuel chamber; and a water outlet connection with one of the manifolds.
  3. In a water heater a header provided with a water chamber; a water supply connected with said chamber; a manifold member having open connection with said chamber; a manifold having a closed connection with said header; a series of separate heating coils interposed between and connected with said manifolds; a header provided with a fuel chamber located below the coils, said header being supported by the manifolds; a flue member extending through the coils; 65 burners connected with said fuel chamber; a casing surrounding the headers, manifolds, coils, and burners for confining the heat; a fuel supply member connected with the fuel chamber; and a water outlet connected with 70 one of the manifolds.

CHRISTOPHER C. WEAVER.
